UNITED STATES PATENT OFFICE.

CHRISTIAN EVENSEN, OF CHOTEAU, MONTANA.

DOOR-CATCH.

1,203,595.

Specification of Letters Patent. Patented Nov. 7, 1916.

Application filed March 13, 1916. Serial No. 83,852.

To all whom it may concern:

Be it known that I, CHRISTIAN EVENSEN, a subject of the King of Norway, residing at Choteau, in the county of Teton and State 5 of Montana, have invented a new and useful Door-Catch, of which the following is a specification.

My invention is intended for use on doors of cabinets, cupboards, and the like, and the 10 objects of my improvement are to provide a device which will firmly secure a door by the simple act of pushing it shut, and which will unfasten the door by the simple act of pulling outwardly on the knob, thus making 15 unnecessary either a twisting or a sidewise motion on the knob before pulling outwardly.

Another object is to provide a catch which will present a neat appearance on the 20 outside of the door, by placing practically all working parts inside.

A practical form of my invention as applied to a cupboard having doors and shelves of wood, is illustrated in the accompanying 25 drawing. However, the device is equally as well adapted to cabinets, cases, etc., made of metal.

Referring to the drawing: Figure 1 is a front view of a small portion of the two 30 doors with knob and escutcheon in place. Fig. 2 is an inside view of the same small portion of the doors, with the shelf removed to clearly show parts which attach to the doors. Fig. 3 is a view looking upward, being partly in section, taken on the line $\alpha-\alpha$ 35 of Fig. 1, and showing doors closed and catch holding. Fig. 4 is a view taken the same as in Fig. 3, but showing doors unfastened and the right hand one slightly 40 ajar. Fig. 5 is an enlarged side view of the door-plate and plunger assembly, shown as detached from the door and viewed in the direction indicated by the line $y-y$ of Fig. 2. Fig. 6 is a sectional side view taken 45 on the line $z-z$ of Fig. 4.

Similar indices refer to similar parts throughout the several views.

The main body of the door-plate 2 forms 50 the inner guide for plunger 1 and has holes for attachment to door with screws or by other means. In addition, plate 2 has two bent projections, the hook c and the part d , which form the front guide for plunger 1 and act also as the front rest for pushing spring 12. The rear end of spring 12 pushes 55 against washer 11 and pin 10, which latter

is disposed through the plunger and projects a little on either side. Spring 12 is quite light, being just strong enough to retain plunger 1 at its inner limit, with pin 10 60 resting against the plate 2. The main part of plunger 1 is shown to be square, but the smaller part g , extending from the shoulder h forward, is round and has the forward end threaded for attachment of knob 5. Shoulder 65 h , by striking against the rest d just as the inner end of 1 comes flush with the inner surface of 2, serves as a limit to prevent pulling plunger 1 too far. The plunger assembly is shown as fitted to door 20. The 70 escutcheon 6 serves only as an ornament, and may be made in any suitable shape or artistic design. Likewise the knob may be made in various designs. The eye-piece 4 is attached to door 21.

The double-leg catch piece 3 is pivoted (by rivet 8) to the central, circular, raised portion of the plate 7, which latter is attached to the under side of shelf 22. Plate 7 has also two projections, the lug e which 80 serves as a stop to limit the backward rotation of piece 3, and the lug f , upon which one end of torsion spring 9 is hooked. This spring is very light, and is disposed around the central raised portion of 7, and has its 85 other end hooked over the edge of leg a .

Fig. 3 shows the doors fastened. The toe of leg b projects through the eye of piece 4 and the toe of leg a is retained in hook c by means of the plunger 1. Now, by simply 90 pulling on knob 5, the plunger 1 first clears the heel of leg a , then the pull of the hook c on top of the toe a rotates the piece 3 back out of engagement to the position shown in Fig. 4. Spring 9 is just strong enough to 95 retain 3 in this position whenever the doors are open. It is obvious that the pull necessary to open the door is utilized to unfasten the catch, and that the need of either a twisting or a sidewise motion on the knob is 100 eliminated.

In closing the cabinet or cupboard, door 21 is first pushed shut, then followed by door 20. When 20 is about shut, the plunger 1 strikes the bottom of leg a at an angle, which, together with the fact that the line of action is considerably to one side of the pivot point 8, causes the toe of a to move readily into hook c , and piece 3 to rotate about the pivot. During this movement of a in entering the hook c , plunger 1 is forced back against the action of spring 12, until the 110

door closes and the toe of *a* is clear back in the hook *c*, whereupon plunger 1 jumps into place back of the heel of leg *a*, thus securing the doors.

5 In cases where there is one door only, piece 4 and leg *b* are unnecessary and are to be left off. These parts are most needed in those cases where the door 20 does not overlap door 21. It is plain that when used on a 10 pair of doors, my invention takes the place of both elbow-catch and cupboard-turn or catch, and that the number of motions used in opening the doors is appreciably reduced.

I claim:

15 In a door catch, a foot-shaped arm, being pivoted at its inner end to shelf or case, and having its longitudinal center line disposed

obliquely to the plane of the closed door; in conjunction with door parts comprising a spring-actuated plunger and an adjacent 20 hook so located that when the door is being closed, the inner end of the plunger strikes the arm near its outer end, the aforesaid oblique disposal of the arm, together with the closing movement of the door, causing 25 the arm to engage the hook, in which engagement the arm and the hook are retained by the plunger, all substantially as described for the purpose specified.

CHRISTIAN EVENSEN.
